UNITED STATES PATENT OFFICE.

JOHN E. GREENWOOD, OF UTICA, NEW YORK.

TROLLEY-POLE HEAD.

SPECIFICATION forming part of Letters Patent No. 767,939, dated August 16, 1904.

Application filed August 29, 1903. Serial No. 171,267. (No model.)

To all whom it may concern:

Be it known that I, JOHN E. GREENWOOD, a citizen of the United States, residing at Utica, in the county of Oneida and State of New York, have invented new and useful Improvements 5 in Trolley-Pole Heads, of which the following is a specification.

My invention has relation to new and useful improvements in trolley-pole heads for over-head electric railways, and more especially to 10 heads of that class which embody a plurality of wheels or collectors which are arranged in tandem and adapted to simultaneously travel upon the line wire or conductor.

15 The object of the invention is to construct a head of the character mentioned which will provide for an operative contact of the collectors with the line - wire without regard to curves, inequalities, and obstructions therein 20 and which will not become displaced by the swaying movement of the car during its progress along the line.

25 The invention consists of a trolley-pole having a flexible terminal on which is movably mounted a cap-piece carrying oppositely-disposed members provided with collectors, said members being independently movable to cause them to readily adapt themselves to the line-wire, and means to limit the movement of 30 the members and to maintain the latter in longitudinal alinement.

35 I have fully and clearly illustrated my invention in the accompanying drawings, forming a part of this specification, and wherein—

Figure 1 is a view in side elevation of a trolley-pole and head embodying my invention and showing the same in operative contact with the wire. Fig. 2 is a central vertical longitudinal section through the invention. Fig. 3 40 is a central transverse vertical section. Fig. 4 is a section on the line 4-4 of Fig. 1, and Fig. 5 is a perspective view of one of the wheel-harps.

Referring to the drawings, 1 designates the 45 upper end of a trolley-pole, which is formed with a recess or socket 2, in which is seated and rigidly secured, by means of transverse bolts 3, one end of a flexible bar or member 4, which I have shown as consisting of a flat leaf- 50 spring which is arranged to lie in a vertical

plane. This member extends vertically for the required distance in order to bring it into proximity to the line-wire and is formed at its upper free end or terminal with an enlarged head 5, which is formed with a transverse aperture 6, substantially as shown in Fig. 3 of the drawings.

7 designates a cap-piece which is constructed to support and carry the collector-carrying members and the means for limiting their movement and maintaining them in longitudinal alinement. This cap-piece is formed with depending arms 8, which are spaced apart from each other and are adapted to be arranged upon either side of the head 5 on the pole, to which they are pivotally connected by means of a bolt 9, which is projected transversely through the arms and the aperture 6 in the head 5 and is secured in position by means of a nut 10. Rising from the sides of the body of cap-piece are oppositely-disposed vertical members 11, which extend upwardly for a short distance and are connected at their top portions by means of a transverse member 12, which serves to strengthen and brace the members 11, the said vertical members and transverse member being so arranged as to provide a space 13 through the cap-piece, which is substantially rectangular in cross-section.

Projected downwardly through apertures in the member 12, extending across the space 13 and threaded into apertures 14 in the body of the cap-piece, are vertical pivot pins or bolts 15, upon each of which is pivotally mounted one end of a horizontally-disposed member 16, the said members being directed, respectively, in opposite directions, so that one member extends in front and the other in rear of the cap-piece. At the free ends thereof each 90 of the members 16 is formed with vertical arms 17, which are spaced apart from each other and are formed at their upper ends with apertures 18 to receive a transverse pin 19, upon which the trolley-wheel 20 is rotatably mounted.

It will be seen from the above description, taken in connection with the drawings, that the wheel-carrying members, owing to their pivotal connection with the head, are free to 100

swing laterally in order to adapt themselves to the curves in the line-wire, so that the wheels carried thereby will run straight upon the wire, and that said members are independent of each other in their movement, so that one in passing from a curve onto a straight wire will immediately assume a straight position without regard to the collector, which still remains on the curve.

10 For the purpose of limiting the lateral swing of the members 16 and returning them into longitudinal alinement when passing from a curved wire onto the straight line and for maintaining them in alined relation I provide 15 springs 21 21, which are rigidly secured at their central portions to the vertical members 11 of the cap-piece and upon the inner face thereof, substantially as shown in the drawings. From the point at which they are secured to the cap-piece the ends of the springs are directed in opposite directions in front and rear of said cap-piece and extend for a short distance beyond the ends of the members 16, where the said springs are slotted, as 20 at 22, and secured together by means of headed fastenings 23, projected through the said slots, the slots providing for the free movement of the springs when the members 16 are swung on the pivots. As shown in the drawings, for a distance adjacent the end portions 25 the springs 21 are directed inwardly into engagement with the sides of the said members 16, in which position they are held by the fastenings 23 in order that the force thereof will be exerted directly and positively against said members. It will be seen that when the members 16 are swung laterally to accommodate the wheels to the course of the wire the movement thereof will be limited by the springs 21 30 and that in passing from a curved portion of the wire to the straight line the force of the springs will be exerted against said members to return them to normal position—that is, in longitudinal alinement.

40 Upon the lower side of the member 16, which is in front during the progress of the car, is provided an eye 24, to which is secured one end of the trolley-rope 25, which is divided into two strands 26, which pass through 45 guide-eyes 27 on the flexible bar 4. By this arrangement in manipulating the rope to place the collectors in engagement with the wire the pull exerted on the rope will serve to swing the cap-piece on its pivots to bring the members 16 in proper horizontal position to permit the simultaneous contact of the collectors with the wire.

In providing the upper end of the pole with

the flexible member 4, upon which the head is mounted, it will be seen that the lateral displacement of the head from the wire incident to the swaying of the car is obviated. In passing obstructions in the line-wire the head by being pivoted will upon striking said obstructions be tilted to permit the collectors to ride thereunder and will again assume a horizontal position as soon as it passes onto the straight wire and be held thereby by the upward force exerted by the spring devices (not shown) with which the trolley-poles are usually provided.

Having thus fully described my invention, what I claim as new is—

1. The combination with a trolley-pole, of a cap-piece, horizontal oppositely-disposed collector-carrying members pivoted to the cap-piece, and flat springs secured at their central portions to the cap-piece the end portions of the springs engaging opposite sides of the said members to maintain them in longitudinal alinement.

2. The combination with a trolley-pole, of a cap-piece, horizontal oppositely-disposed collector-carrying members pivoted to the cap-piece, flat springs secured at their central portions on opposite sides of the cap-piece, said springs engaging the sides of the members and projecting beyond the free ends thereof, said springs being movably connected at a point beyond the members.

3. The combination with a trolley-pole, of a cap-piece, horizontal oppositely-disposed collector-carrying members pivoted to the cap-piece, flat springs secured at their central portions on opposite sides of the cap-piece, said springs engaging the sides of the members and projecting beyond the free ends thereof and having slots therein and bolts projecting through the slots.

4. The combination with a trolley-pole, of a cap-piece provided with vertical spaced members, horizontal oppositely-disposed collector-carrying members pivoted to the cap-piece between the spaced members, flat springs secured at their central portions to the spaced members, said springs engaging the sides of the members and projecting beyond the free ends thereof and having slots, and bolts projecting through the slots.

In testimony whereof I affix my signature in presence of two witnesses.

JOHN E. GREENWOOD.
